UNITED STATES PATENT OFFICE

169,470

COMBINED HAIR CURLER AND COMB

Thomas H. Bimrose, Beverly Hills, Calif.

Application August 11, 1952, Serial No. 20,968

Term of patent 14 years

(Cl. D86—8)

To all whom it may concern:

Be it known that I, Thomas H. Bimrose, a citizen of the United States of America, residing in the city of Beverly Hills, in the county of Los Angeles, State of California, have invented a new, original, and ornamental Design for a Combined Hair Curler and Comb, of which the following is a specification, reference being had to the accompanying drawing, forming a part thereof.

Fig. 1 is a perspective view to a larger scale of a combined hair curler and comb, showing my new design;

Fig. 2 is an end view thereof from the curler end;

Fig. 3 is a side elevational view of the same;

Fig. 4 is a plan view of the comb and spindle, with the rotor removed; and

Fig. 5 is a perspective view of the rotor removed from the comb.

I claim:

The ornamental design for a combined hair curler and comb, substantially as shown and described.

THOMAS H. BIMROSE.
